CLAIM

The ornamental design for a vehicle back light, as shown and described.

DESCRIPTION

FIG. 1 is a perspective view of an automotive back light. The drawings and descriptions represent the left side.

FIG. 2 is a front view thereof;

FIG. 3 is a side view thereof; and,

FIG. 4 is a top view thereof.

The broken line portions shown in FIGS. 1-4 illustrate environmental subject matter only and form no part of the claimed design.

1 Claim, 4 Drawing Sheets
